(57) **CLAIM**

I claim the ornamental design for a handheld skin cleansing device, as shown and described.

DESCRIPTION

FIG. 1 is a perspective view of a handheld skin cleansing device showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown in the drawings are for the purpose of illustrating portions of the handheld skin cleansing device, which form no part of the claimed design.
